UNITED STATES PATENT OFFICE.

ARTHUR R. ZACHERT, OF NEW BEDFORD, MASSACHUSETTS, ASSIGNOR TO ATLAS TACK CORPORATION, OF FAIRHAVEN, MASSACHUSETTS, A CORPORATION OF NEW YORK.

BUTTON.

Application filed February 9, 1927. Serial No. 166,910.

This invention relates to buttons, more particularly those formed of metal such as aluminum, the present invention having for its object to provide a light weight but substantial button of good appearance which may be produced expeditiously and cheaply, and, more particularly, from relatively light weight sheet stock.

To accomplish this object a blank of sheet metal is formed up into a button having a hollow rim presenting rounded edges smooth and concentric with a dished portion within the rim providing a space for the stitches and which holds the hollow rim spaced from the face of the goods to which the button is applied.

For a more complete understanding of this invention, reference may be had to the accompanying drawings in which

Figure 1 is a top plan of one form of the button.

Figure 2 is a cross section on line 2—2 of Figure 1.

Figures 3 and 4 are views similar to Figure 2, but showing modifications.

Figure 5 is a cross section on line 5—5 of Figure 4.

Referring first to Figures 1 and 2, the button is formed of relatively thin sheet metal dished at its central portion to produce a central web at 10, herein shown as circular in outline, terminating in an upstanding marginal annular wall 11, the upper edge of which is folded outwardly and downwardly as at 12 and then inwardly as at 13 into substantial contact with the outer face of the portion 11 above its lower edge, thus forming a hollow bead or rim for the button. The central web portion 10 is perforated as at 14 with stitch-receiving holes, the edges of these holes preferably being rounded as at 15 to prevent cutting of the stitches passing from one hole to the other.

As shown in Figure 2 the central web portion is downwardly dished but if desired it may be formed flat as shown in Figure 3. In Figure 3 also the marginal bead is shown as formed of different cross section than that shown in Figure 2, its upper face 20 presenting a gradual curve, the maximum distance from the base of the button being substantially half way between the maximum and minimum diameters of the bead, while in the construction shown in Figure 2 the maximum thickness of the rim portion of

the button is closely adjacent to its minimum diameter portion and its upper face is substantially flat.

In place of forming the stitch-receiving holes as shown in Figures 2 and 3, they may be formed in the manner disclosed in Figures 4 and 5. In these figures it will be seen that substantially semicircular cuts 21 are made through the central web portion thus partly severing semicircular tabs 22 which are struck upwardly from the central web portion and then bent downwardly against the outer face thereof, thus forming rounded edges 23 diametrical with respect to the portions partly cut, these edges being so disposed as to have engagement with stitches passing from one hole to the other. Whether the holes are formed by completely severing or by partially severing and then bending, the central dished portion of the button provides a space to receive the stitches so that they do not project beyond the rim portion of the button. It is of course evident that any desired number of stitch-receiving holes may be provided.

The rim portion being formed by folding the sheet metal stock so that its edges substantially abut the upstanding wall portions of the dished central portion, produces a smooth rounded rim portion for the button which because it is hollow is considerably lighter than were it made solid. The edge portions of the stock being in substantial contact with the annular upstanding wall portion, the exposure of rough or sharp edges is avoided without special treatment of the cut edges of the blank and the back face of the button about the used portion presents a substantially flat face to the fabric about the button hole. The button thus closely simulates a bone or horn button of good quality.

Having thus disclosed certain embodiments of this invention it should be evident to those skilled in the art that various changes might be made therein without departing from its spirit or scope as defined by the appended claims.

I claim:

1. A sheet metal button comprising a central circular portion pierced for the reception of securing stitches, and an annular wall portion about the margin of said central portion, the edges of said annular portion being rolled back into substantial con-

105

110

tact with the outer face of said wall portion to form an annular hollow bead.

2. A sheet metal button comprising a central circular portion pierced for the reception of securing stitches and an annular wall portion about the margin of said central portion, the edges of said annular portion being folded back into substantial contact with the outer face of said wall portion above its juncture with said central portion to form an annular hollow bead spaced above the work to which said button may be attached.

3. A button comprising a thin web having spaced portions partly severed therefrom and bent toward each other against the face

of said web to form stitch-receiving holes presenting the folded edges of said partly severed portions to stitches passing from one to another of said holes.

4. A button comprising a thin web having spaced substantially semicircular portions partly severed therefrom and bent toward each other along their diametrical edges and against said web to form spaced stitch-receiving openings presenting the rounded and thickened edges at the bend for engagement with stitches passing from one to another.

In testimony whereof I have affixed my signature.

ARTHUR R. ZACHERT.
